[57] CLAIM

The ornamental design for an article of flatware, as shown and described.

DESCRIPTION

FIG. 1 is a front elevation view of an article of flatware showing my new design as embodied in a fork;

FIG. 2 is a right side elevational view of FIG. 1;
FIG. 3 is a left side elevational view of FIG. 1;
FIG. 4 is a rear elevational view of FIG. 1;
FIG. 5 is an end elevational view from the top of FIG. 1;

FIG. 6 is an end elevational view from the bottom of FIG. 1;
FIG. 7 is a front elevational view of an article of flatware showing my new design as embodied in a pickle fork;

FIG. 8 is a right side elevational view of FIG. 7;

FIG. 9 is a left side elevational view of FIG. 7;

FIG. 10 is a rear elevational view of FIG. 7;
FIG. 11 is an end elevational view from the top of FIG. 7;

FIG. 12 is an end elevational view from the bottom of FIG. 7;

FIG. 13 is a front elevational view of an article of flatware showing my new design as embodied in a spoon;
FIG. 14 is a right side elevational view of FIG. 13;

FIG. 15 is a left side elevational view of FIG. 13;

FIG. 16 is a rear elevational view of FIG. 13;

FIG. 17 is an end elevational view from the top of FIG. 13;

FIG. 18 is an end elevational view from the bottom of FIG. 13;

FIG. 19 is a front elevational view of an article of flatware showing my new design as embodied in a vegetable spoon;

FIG. 20 is a right side elevational view of FIG. 19;

FIG. 21 is a left side elevational view of FIG. 19;

FIG. 22 is a rear elevational view of FIG. 19;
FIG. 23 is an end elevational view from the top of FIG. 19;

FIG. 24 is an end elevational view from the bottom of FIG. 19;

FIG. 25 is a right side elevational view of an article of flatware showing my new design as embodied in a sauce ladle;

FIG. 26 is a rear elevational view of FIG. 25;

FIG. 27 is a front elevational view of FIG. 25;

FIG. 28 is a left side elevational view of FIG. 25;

FIG. 29 is an end elevational view from the top of FIG. 25;

FIG. 30 is an end elevational view from the bottom of FIG. 25; and

FIG. 31 is an enlarged cross-sectional view taken on line 31—31 of FIG. 1.

The distinguishing feature of my new design resides in the handle configuration.
